UNITED STATES PATENT OFFICE

GEORGE HEESEN, OF TECUMSEH, MICHIGAN.

IMPROVED CHAIR-SEAT.

Specification forming part of Letters Patent No. 69,430, dated October 1, 1867.

To all whom it may concern:

Be it known that I, GEORGE HEESEN, of Tecumseh, in the county of Lenawee and State of Michigan, have invented a new and Improved Chair-Seat; and I do hereby declare that the following is a full and exact description thereof, which will enable others skilled in the art to make and use the same, reference being had to the accompanying drawing, and to the letters of reference marked thereon.

This invention relates to a new and improved seat for chairs, settees, &c.; and consists in substituting paper twine for flags hitherto used for such purpose. The seat is constructed in precisely the same way as the flag seat.

The accompanying drawing represents a plan or top view of my invention.

The seat-frame may be constructed so as to form a permanent fixture with the legs and back of the chair, or it may be made separately, and the paper-twine seat made or formed in

the frame, so that it may be applied to or inserted in any chair-frame. The sides and ends of the seat-frame are covered by the paper twine A, the corners B of the seat-frame being exposed, as usual. The twine A may be constructed in the usual way. It should be well twisted, and made of good Manila paper.

The chair-seat thus made is very strong and durable, and may be manufactured at a very moderate cost.

Having thus described my invention, I claim as new and desire to secure by Letters Patent—

As an improved article of manufacture, a chair-seat formed or constructed of paper twine, substantially as set forth.

GEORGE HEESEN.
